(57) **CLAIM**

I claim the ornamental design for an outlet assembly for packaging container, as shown and described.

DESCRIPTION

FIG. 1 is a front view of an outlet assembly for packaging container showing my new design;

FIG. 2 is a rear view thereof;

FIG. 3 is a right side view thereof;

FIG. 4 is a left side view thereof;

FIG. 5 is a top plan view thereof;

FIG. 6 is a bottom view thereof;

FIG. 7 is a perspective view thereof;

FIG. 8 is an exploded perspective view thereof;

FIG. 9 is a front view thereof, shown in an alternate configuration of use;

FIG. 10 is a perspective view thereof, shown in an open configuration;

FIG. 11 is a perspective view thereof, shown with the inner lid removed;

FIG. 12 is a perspective view thereof, shown in a closed configuration in an unclaimed environment of use;

FIG. 13 is a perspective view thereof, shown in an open configuration; and,

FIG. 14 is a perspective view thereof, shown in an open configuration.

The broken lines in the drawings represent unclaimed environmental subject matter and form no part of the claim.
